UNITED STATES PATENT OFFICE.

JOHN L. KING, OF NEW YORK, N. Y., ASSIGNOR TO ROTARY KING SAFETY RAZOR COMPANY, OF NEW YORK, N. Y., A CORPORATION OF DELAWARE.

SAFETY-RAZOR.

1,398,379.

Specification of Letters Patent. Patented Nov. 29, 1921.

Application filed September 13, 1920. Serial No. 409,871.

To all whom it may concern:

Be it known that I, JOHN L. KING, a citizen of the United States, residing at New York, Kings county, New York, have invented certain new and useful Improvements in Safety-Razors, of which the following, taken in connection with the drawings, is a description.

My invention has for its object the production of a safety razor of the class known as the reciprocating blade type, wherein the blade is given a shearing movement while in operation.

It is also an object of my invention to provide a razor of this kind which shall be simple in its construction, comprise the fewest possible parts, and be efficient in its operation, and to provide a simple form of blade adapted to be used particularly with this razor.

A further object of my invention is to provide a razor of this class having a very simple form of construction for effecting a reciprocation of the blade, but one which is very accurately adjusted to function in its operation.

A further object of my invention is to provide an improved blade for use in a razor of this kind, one which has two cutting edges whereby the usefulness of the blade is increased 100%, the means for actuating said blade on the razor head being centralized with respect to the blade and thus permitting either edge thereof to be adjusted in position for use in shaving.

These and other features of advantage will be apparent to those skilled in the art to which this invention pertains, and in the accompanying drawings I have illustrated what I now consider the preferred form of an embodiment of my invention, not wishing to be limited to the exact details there shown as I contemplate such changes as may be made within the scope of the accompanying claims, and in this drawing—

Figures 1 and 2 respectively are a side and front elevation of my razor,

Fig. 3 is a top plan view,

Fig. 4 is a view of the head or supporting frame with the rotating member and blade removed,

Fig. 5 is an enlarged sectional detail of the reciprocating mechanism,

Fig. 6 is a plan view of the blade.

Referring to the drawings 7 represents the handle of my razor which is preferably knurled or roughened as shown to facilitate using the same. Mounted upon one end of this handle is the razor supporting frame 8, one side, 9, of which is fixedly secured to the end of the handle, the other side, 10, being inclined at an angle to the fixedly secured portion of said frame extends downwardly and away from the handle of the razor.

This downwardly bent portion 10 of the frame is provided with a slot 11 in the center thereof for a purpose hereinafter described. There is also provided in this inclined portion of the supporting member an elongated opening 12, and a plurality of small openings 13, which provide air passages between said frame and the blade to be supported thereon.

14—14 are guide posts extending upwardly from the inclined portion of the frame member 8 and project into openings arranged in the blade to receive the same, and by means of which the blade is kept in perfect alinement during the reciprocating operation.

The free edge of the downwardly inclined portion 10 of the supporting member 8, is serrated and is concave on the longitudinal edge thereof.

Bent upwardly from the attached portion of the supporting frame 8 are the bearing members 15—15, between which is journaled a cam roller 16. The peripheral face of this roller is roughened in any desired manner to facilitate the frictional engagement with the face when the device is in operation.

17 is a peripheral cam groove preferably arranged at or near the center of the roller 16, the cam surface thereon being perforated to permit an oscillating motion to the blade 95 at predetermined distances.

Pivottally attached at 18 to what I shall term the rear edge of the supporting frame, 8, is an oscillating member 19, which projects across the supporting frame 8 beneath the peripheral cam groove 17 on the roller 16. A projection 20 on the oscillating member 19 extends into the path of the cam groove 17. The oscillating member 19 extends through an opening 21 in the supporting frame to a point directly beneath the center of the inclined portion 10 of the frame. This oscillating member is curved

at the end thereof as shown in Fig. 5 and carries a projection or head 22 which engages the opening 23, in the center of the blade 24.

5 The blade 24 is provided with slots or elongated openings 25 arranged in longitudinal alinement with the central opening 23.

The guide posts 14—14 extend into this opening 25 and serve to keep the blade 24 in 10 longitudinal alinement while the razor is in use.

A blade retaining member 26 is mounted upon the supporting frame and normally rests above the blade as shown in Figs. 1 and 15 2. A pair of leaf springs 27 attached at one end thereof to the inner side of the frame 8 extend to the ends of the members 28 of the blade retaining member 26. To remove the blade from the supporting member the 20 retaining member is raised upwardly against the force of the springs 27 until the ends of the members 28 have turned on the frames which serve to hold said retaining member in elevated position, when the blade may be 25 removed from the supporting frame, and a new one placed thereon.

In Fig. 5 I have shown a plan view of the blade 24 from which it will be seen that I have provided a blade having two cutting 30 edges 29—30 with openings 25—25 and 23 arranged in longitudinal alinement with each other so that the blade may be placed in operative position upon the retaining projections on the supporting frame with either 35 edge in shaving position.

When in operation the roller 16 contacts with the face being shaved and is thereby rotated. The rotation of said roller through the cam surface in the groove 17 actuates 40 the oscillating member 19, which is in direct contact with the blade 24 through the center opening 23 and transmits thereto a reciprocating or shearing motion to said blade, which makes the process of shaving much 45 more easily and quickly accomplished than with a blade having only a scraping action.

I claim:

1. In a safety razor, the combination of a 50 supporting member, a blade movably mounted thereon, a cam roller mounted in bearings formed in said supporting member, an oscillating member pivotally secured at one end thereof to the rear edge of the supporting member, a projection on said oscillating member engaging the cam roller, the free end of said oscillating member extending downwardly through an opening in the supporting member, a projecting head on the free end of said oscillating member engaging

the blade and transmitting a reciprocating motion thereto.

2. In a safety razor, the combination of a supporting member fixedly secured to the end of the razor handle and having a portion thereof bent at an incline to the handle, a 65 cam roller mounted thereon, a blade movably mounted on the inclined portion of the supporting frame, said inclined portion of the supporting frame having openings therethrough between said frame and blade to 70 provide an air space, an oscillating element pivotally attached to the rear edge of said supporting member and extending downwardly through an opening in the supporting frame, an upwardly projecting head on the end of said oscillating element engaging said blade through an opening in the supporting frame and having engagement with the blade, and means for actuating said oscillating element and blade.

3. In a safety razor, the combination of a supporting member fixedly secured to the end of the razor handle and having a portion thereof bent at an angle to the handle, a cam roller and a blade movably mounted on 75 said member, guide posts rising from said inclined portion and extending through openings formed in the blade, an oscillating member having one end thereof movably attached to the rear edge of the supporting member, a projection on said member extending into the cam on said roller, the free end of the oscillating member extending downwardly through an opening in the supporting member, and an upwardly extending 80 projection on said oscillating member registering with an opening in the aforesaid blade whereby motion is transmitted thereto.

4. In a safety razor, the combination of a supporting member, fixedly secured to the 85 end of the razor handle and having a portion thereof bent at an angle to the handle, a cam roller and a blade movably mounted on said supporting member, an oscillating member pivotally mounted at one end thereof to the 90 rear edge of the supporting member, means carried by said oscillating member having operative engagement with the cam roller, the opposite end of said oscillating member extending downwardly through an opening 100 in the supporting member, a projection thereon having engagement through an opening in the center of the blade, whereby an oscillating motion is transmitted to the blade when the cam roller is actuated.

In testimony whereof I have signed this specification.

JOHN L. KING.
